UNITED STATES PATENT OFFICE.

WARREN B. FLANDERS, OF PHILADELPHIA, PENNSYLVANIA, ASSIGNOR TO WESTINGHOUSE ELECTRIC AND MANUFACTURING COMPANY, A CORPORATION OF PENNSYLVANIA.

GOVERNING MECHANISM FOR STEAM TURBINES.

Application filed June 9, 1920, Serial No. 387,538. Renewed January 9, 1926.

My invention relates to improvements in governing mechanism for steam turbines, and more particularly to that class of governing mechanism employed to automatically 5 shut off the steam supply to the turbine when a predetermined overspeed is reached.

The object of my invention is the provision of manually controlled means whereby the governor mechanism may be made 10 to operate at a speed below that for which it is adjusted, so that the condition of operation of the mechanism may be readily determined, and is especially intended for the 15 purpose of testing the mechanism at any desired time.

I attain these objects by the mechanism illustrated in the accompanying drawing, in which Fig. 1 is a sectional view through a turbine shaft and housing showing details 20 of a governing mechanism with my improvement applied thereto; Fig. 2 is a detail view showing parts of my improvement in a different operative position; and Fig. 3 is a 25 sectional view showing the fluid bath for my improved governor.

The overspeed governing mechanism, hereafter referred to as the auto-stop governor, is mounted on a turbine-driven shaft 10. The end of the turbine-driven shaft 10 is 30 provided with an extension 11 having a diametral recess 12. The recess 12 has two shoulders 13 and 14 and is threaded at 15 to receive the retainer 16, which is provided with a guide opening in which the weight 35 17 may slide. The retainer 16 holds the spring 18 in place, and due to the threaded connection thereof to the recess, the tension of the spring 18 may be readily adjusted. The spring 18 also bears against piston 19 40 of the weight or trip element 17 to maintain the piston in contact with shoulder 14. The collar 20 tightly fits in the recess 12 against the shoulder 13 and overhangs the latter in order to limit the travel of the piston 19. 45 The weight or trip element 17 is thereby prevented from passing beyond the point necessary to trip the lever 21 which acts through a suitable mechanism to shut off the steam supply to the turbine. The weight 50 17 has its center of gravity, indicated, for example, at 17', arranged to one side of the

axis of rotation of the shaft 10 so that it is responsive to centrifugal force to move out and trip the element 21.

A clearance space 22 is provided below the 55 piston 19 which communicates with the exterior of the turbine-driven shaft through the eccentric passage 23. A similar eccentric passage 24 is provided on the opposite side of the shaft 10 which communicates 60 with the passage 23 through the passage 25. The axial passage 26 communicates between the exterior of the shaft 10 and the passage 25 and is chamfered at its entrance as shown.

In the casing 30, adjacent to the end of 65 the turbine shaft 10, is mounted a mechanism whereby the ends of the passages 23 and 24 may be closed. This mechanism consists of a rod 31 provided at one end with a threaded extension of diminished diameter 32 and at 70 the other end with a flange 33. The rod 31 is supported with reference to the casing 30 by means of the two bushings 34 and 35. In the space 36 between bushings 34 and 35 and on rod 31 is mounted a spring 37 resting against bushing 34 and pressing against collar 38 of rod 31. Mounted on the end of rod 31 is an annular member 39 flexibly connected to the flange 33 by means of the diaphragm 40. The diaphragm 40 is secured 80 to the annular member 39 by a series of screws 41 and to the flange 33 by a washer 42 and rivet or other means 43. The annular member 39 is provided with one or more entrance passages 44 which permit oil 85 to enter the space between the inside of the annular member 39 and the diaphragm 40.

The spring 37 pressing against collar 38 of rod 31 serves to keep the annular member 39 in contact with the end of the shaft 90 10 thereby closing the ends of the passages 23 and 24. In this position the annular member 39 is prevented from rotating with the shaft 10 by means of the pin 45 mounted in rod 31 and engaging two slots 46 cut in 95 opposite sides of the bushing 34. On the extension 32 of rod 31 may be mounted a suitable handle 47 or hand-wheel held in place by nut 48 and adapted to control the annular member 39. To disengage the annular member 39 from the end of the shaft 10 it is simply necessary to pull on handle 47 100

until pin 45 clears the face of bushing 34 and then turn rod 31 until pin 45 can rest against the solid face of bushing 34.

The main governor of a steam turbine may not always function properly and in such a case it is desirable to provide an automatic stop governor to shut off the steam supply to the turbine when too high a speed is reached. An auto-stop governor is generally designed to become effective at about 10% overspeed. If the turbine has been running at constant speed for a long time and the auto-stop governor has not been called upon to operate, it is not uncommon for the auto-stop governor to get stuck which of course renders it practically useless. This might cause serious damage to the turbine on account of overspeeding.

In order to determine the working conditions of the auto-stop governor, the testing mechanism has been devised as herein described. This mechanism will function only when the end of the turbine shaft is run in oil. When the annular member 39 is in the disengaged position, oil will enter passage 26 and will have a free path through passage 25 and out through passages 23 and 24. In order to test the auto-stop governor it is simply necessary to turn handle 47 until pin 45 registers with slots 46. The spring 37 will then force the annular member 39 against the end of the turbine shaft 10 thereby closing passages 23 and 24. Oil entering through passage 26 will then fill passages 23, 24, 25 and the clearance space 22 below piston 19. Due to the centrifugal force caused by the rotation of the turbine shaft, pressure will be built up in the column of oil in passage 25 which will be transmitted through the oil to the clearance space 22. This pressure acting against piston 19 together with the centrifugal force acting on weight 17 will be sufficient to cause the weight 17 to move out and trip the element 21 thereby shutting off the steam supply to the turbine. If the oil pressure does not cause the mechanism to operate, it will mean that the governing mechanism is not in the proper working condition, and the cause of the trouble must be investigated.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In an auto-stop governing mechanism, the combination of an eccentrically weighted tripping member, means for resisting movement of the tripping member in response to

centrifugal force, means for developing centrifugal force of fluid for application to the tripping member in opposition to said resisting means, controlling means for rendering the centrifugal fluid pressure developing means effective or ineffective, and means for maintaining the latter means normally in ineffective position. 70

2. The combination with an auto-stop governor having an eccentrically weighted tripping member and a spring for resisting movement of the latter in response to centrifugal force, of means for developing centrifugal force of fluid pressure for application to the tripping member in opposition to the spring, controlling means for rendering the centrifugal fluid pressure developing means effective or ineffective, and a spring for maintaining the latter means in ineffective position. 75

3. An auto-stop governor comprising a rotary element having a diametral recess and axial and eccentric passageways in communication therewith, an eccentrically weighted trip element within said recess and having a piston connected thereto, adjustable tensioning means to secure operation of the trip element at a predetermined speed, an annular member adapted to close the eccentric passage, and means cooperating with the annular member to maintain it either in operative or inoperative position. 90

4. An auto-stop governor comprising a rotary element adapted to be immersed in a liquid, an eccentrically weighted trip element carried thereby and capable of moving to tripping position on attaining a predetermined speed, a piston secured to said trip element, said rotary element having axial and eccentric passages communicating with the space beneath the piston, a ring element adapted to close the eccentric passages and having ports to afford communication of the axial passage with the exterior when the ring is in closed position, a flexible diaphragm connected to the ring and manually controlled means connected to the diaphragm for moving the ring into and out of position. 100

5. In a governor mechanism the combination of a rotary element having a recess with a piston chamber at the lower end, an eccentrically weighted element within the recess and having a piston fitting within the piston chamber, spring means associated with said element to secure movement thereof to tripping position upon attainment of a predetermined speed by the rotary element, said rotary element having axial and eccentric passages in communication with the undersurface of the piston and means to close the eccentric passages including a member having ports to afford communication between the axial passage and the exterior of the rotary element, a flexible diaphragm 110

secured to the member, a spring pressed means to exert pressure against the diaphragm to maintain the member in contact with the rotary element to close the eccentric passages.

6. An auto-stop governor comprising a rotary element having a diametral recess with a piston chamber and clearance space at the bottom thereof, an eccentrically weighted trip element within the recess and having a piston fitting within the piston chamber, adjusting means cooperating with the trip element to secure tripping at a predetermined speed, said rotary element having axial and eccentric passages communicating with the clearance space, a ring adapted to close the eccentric passages and having one or more ports to afford communication between the axial passage and the exterior of the ring, manual means to withdraw the ring from closing position, and spring means to maintain the ring in the closing position.

7. An auto-stop governor comprising a rotary element adapted to be immersed in a liquid having a diametral recess with a piston chamber and clearance space at the bottom thereof, an eccentrically weighted trip element within the recess and having a piston fitting within the piston chamber, adjusting means cooperating with the trip element to secure tripping at a predetermined speed, said rotary element having axial and eccentric passages in communication with the clearance space below the piston, means to close the eccentric passages, pressure means to maintain the closure means in closed position, and means to move and maintain the closure means in ineffective position.

8. An auto-stop governor comprising a rotary element adapted to be immersed in a fluid and having a diametral recess with a piston chamber and clearance space at the bottom thereof, and eccentrically weighted trip element within the recess and having a piston portion fitting within the piston chamber, adjusting means cooperating with the trip element to secure tripping at a predetermined speed, said rotary element having axial and eccentric passages in communication with the clearance space beneath the piston portion, a ring to close the eccentric passages and having passages to afford communication between the axial passage and the exterior thereof, a flexible diaphragm secured to the ring, and spring-pressed control means connected to the diaphragm.

9. An auto-stop governor comprising a rotary element having a diametral recess with a piston chamber and clearance space at the bottom thereof and adapted to be immersed in a liquid, an eccentrically weighted trip element within the recess and having a piston portion fitting within the piston chamber, adjusting means cooperating with the trip element to secure tripping at a predetermined speed,

at a predetermined speed, said rotary element having axial and eccentric passages in communication with the clearance space beneath the piston portion, closure means for the eccentric passages, control means flexibly connected with the closure means, spring means to maintain the closure means in active position, and means to position the control means to maintain the closure means in ineffective position.

10. An auto-stop governor comprising a rotary element having a recess with a piston chamber and clearance space, an eccentrically weighted trip element within the recess and having a piston portion fitting within the piston chamber, said rotary element having eccentric and axial passages within the end thereof and in communication with the clearance space beneath the piston portion, closure means for the eccentric passages having ports to afford communication between the axial passage and the exterior thereof, control means for the closure means flexibly connected thereto, supporting means for the control means, spring means carried by the supporting means and cooperating with the control means to maintain the closure means in active position, pin-and-slot means cooperating with the control means and the supporting means to maintain the closure means in an ineffective position.

11. An auto-stop governor comprising a rotary element having a recess with a piston chamber and clearance space at the bottom thereof and adapted to be immersed in a liquid, an eccentrically weighted trip element within the recess and having a piston portion fitted within the piston chamber, adjusting means cooperating with the trip element to secure tripping at a predetermined speed, said rotary element having eccentric and axial passages in communication with the clearance space beneath the piston portion, a closure ring for the eccentric passage and having passages to afford communication between the axial passage and the exterior thereof, a flexible diaphragm connected to the ring, a spring control means connected to the diaphragm to maintain the closure ring in effective position, and means cooperating with the last named means to withdraw the closure means and maintain it in ineffective position.

12. An auto-stop governor comprising a rotary element having a recess with a piston chamber and clearance space at the bottom thereof and adapted to be immersed in a liquid, a casing element for the rotary element, an eccentrically weighted trip element within the recess and having a piston portion fitting the piston chamber, adjusting means cooperating with the trip element to secure tripping at a predetermined speed, axial and eccentric passages in communication with one end of the rotary element

and with the clearance space beneath the piston portion, a closure ring for the eccentric passages and having passages adapted to afford communication between the axial 10 passage and the exterior thereof, a flexible diaphragm connected to the ring, a rod connected to the diaphragm and passing through the casing element, means acting on the rod to maintain the ring in closing position, and means associated with the rod whereby it may be withdrawn and retained in such a position as to maintain the closure ring ineffective.

13. An auto-stop governor comprising a 15 rotary element having a recess with a piston chamber and clearance space at the bottom thereof and adapted to be immersed in a liquid, a casing element therefor, an eccentrically weighted trip element within the 20 recess and having a piston portion fitting within the piston chamber, adjusting means cooperating with the trip element to secure tripping at a predetermined speed, said rotary element having axial and eccentric 25 passages affording communication between one end thereof and the clearance space beneath the piston portion, a closure ring for the eccentric passages and having passages

adapted to afford communication between the axial passages and the exterior thereof, 30 a control rod flexibly connected to the closure ring, and passing through the casing element to be operative from the outside, an abutment on the rod, a spring between the abutment and a portion of said 35 casing element to exert pressure on the rod to cause the closure ring to be maintained in closing position, means for retracting the rod and means cooperating with the rod and the spring to maintain the rod in retracted position when the latter is withdrawn and turned.

14. The combination with an auto-stop governor having an eccentrically weighed tripping member and means for resisting movement of the latter in response to centrifugal force, of means adapted to develop centrifugal force of fluid pressure and adapted to be normally ineffective, and biased means adapted to be manually operated to render said means effective.

In testimony whereof, I have hereunto subscribed my name this 4th day of June, 1920.

WARREN B. FLANDERS.
